UNITED STATES PATENT OFFICE.

LAURENCE P. SHARPLES, OF WEST CHESTER, PENNSYLVANIA.

CENTRIFUGAL MACHINE AND METHOD.

1,207,230.

Specification of Letters Patent.

Patented Dec. 5, 1916.

Application filed April 27, 1915. Serial No. 24,208.

To all whom it may concern:

Be it known that I, LAURENCE P. SHARPLES, a citizen of the United States, residing at West Chester, in the county of 5 Chester and State of Pennsylvania, have invented certain Improvements in Centrifugal Machines and Methods, of which the following is a specification.

My invention relates to centrifugal machines and methods, and my leading object 10 is to provide improvements in feeding and steadyng centrifugal bowls, more particularly to effect a desired substantially constant relation between the centrifugal force 15 developed and the rate of feeding, with uniformly high efficiency throughout the range of operating speeds.

My improved machine, in its preferred form, comprises, generally stated, a suspended revoluble bowl having a bottom inlet, together with top outlets adapted for effecting air exhaustion that will cause fluid to be lifted by atmospheric pressure through 20 said inlet from a supply beneath it, in combination with mechanisms for steadyng the bottom of the bowl and providing a guard and passageway containing the mouth of 25 said inlet, the fluid to be treated being drawn through the passage and inlet into 30 the revolving bowl by reason of the exhaust through the top outlets.

While the machine is designed particularly for skimming milk and separating cream, it will be understood that it is adapted for more general use.

The invention effects the desideratum of taking and separating liquids at rates varying with the speed of rotation, in a machine that is simple in construction, readily taken 40 down, easily cleaned and readily assembled.

In the accompanying drawings, Figure 1 is a part sectional elevation of a centrifugal separator embodying my invention; Fig. 2 is an enlarged sectional view taken on the 45 line 2—2 of Fig. 1; and Fig. 3 is a broken part sectional elevation of the bottom of the bowl and its case with the supply vessel suspended from the latter.

My improved machine, in the form thereof 50 illustrated in the drawings, comprises a pedestal 1 having the gear case 2 and the bowl case 3 supported thereby.

A tubular bowl 4 is suspended and re-

volved in the case 3 by the spindle 5 journaled in the case 2. The bowl has in the 55 upper end thereof the passage 6 adapted for discharging skim-milk, the free or untrapped passage 7 adapted for discharging cream and regulating the suction, and the air discharge passage 8 extending, from a 60 point within the cream wall, downwardly and outwardly through the top of the bowl to a point beyond the passage 6, to provide efficient means for exhausting air from the 65 bowl.

The bottom of the bowl is provided with an axial boss 9 containing an axial inlet 10 through which an upward draft is created by the exhaust through the top passages due to the centrifugal action, the suction being sufficient to cause milk to be 70 lifted through the inlet from a supply having a level preferably maintained below the boss.

A tubular shell 11 is provided with a 75 conical section 11^a which fits in a conical seat 3^a in the bottom of the case 3 concentric with the boss 9. A ring or bushing 12 is disposed in the shell 11 on the boss 9 and is held against the shell's inwardly extending flange 11^b by a coiled spring 13. The ring, suitably of wood, has a limited lateral movement in the shell under the restraining influence of friction due to the spring's action, whereby the lower end of 80 the bowl is permitted a slight lateral movement and eccentric action under steadyng frictional restraint.

A thimble, comprising the tubular sections 14 and 14^a joined by the shoulder 14^b, 90 supports the spring 13, which rests on the shoulder, the larger upper section 14 telescoping in the lower end of the shell and the lower section 14^a resting on the bottom of the cup or vessel 15 which is provided 95 with the centering boss 15^a disposed within the bottom of the thimble. Ports 14^c in the section 14^a permit liquid to be drawn from the cup, exterior to the thimble, into the chamber within the thimble and shell, 100 whence it is forced by the unbalanced atmospheric pressure through the passage 10 into the bowl and the constituents separated therein are discharged through the passages 6 and 7.

The cup 15 is telescoped on the bottom of 105

the case 3 and suspended therefrom by means of studs 3^b on the case, which engage angular ways 15^b in the cup permitting the parts to be locked together. A second 5 cup 16 is connected to the cup 15 by a passage 17 and is disposed beneath the valve 19 having a port 19^a in the bottom of a vessel 20 which is supported by the pedestal 1. A float 21 in the cup 16 is provided with the 10 stopper 21^a adapted for closing the port 19^a when the valve 19 is open and the liquid in the cups rises to a predetermined level, the float maintaining a constant liquid level 15 below the bowl boss in the preferred operation.

The assembly, which is composed of the ring 12, the shell 11, the spring 13 and the thimble 14, provides a guide for the lower end of the bowl 4 and a passageway for the 20 liquid flowing to the bowl inlet 10. The passageway serves as a guard which prevents the revolving boss 9 from objectionably scattering or agitating the supply, and also restricts the flow of air to the inlet 10, 25 providing a chamber sealed to a degree, so that the suction shall have the desired effect on the liquid and cause it to be lifted into the bowl even when the level of the liquid in the supply cup 15 is wholly below 30 the boss.

The mechanism described, when operated through a comparatively wide range of speeds, draws liquid into the bowl at a rate approximately proportional to the square 35 of the speed of revolution. As the rate of revolution of the bowl effects a corresponding change in the centrifugal force developed, by which the rate of skimming varies, and a corresponding exhaustion of the bowl 40 by which the rate of feeding varies, the desired operation and complete skimming are effected efficiently throughout variations in the speed of the machine, as distinguished from prior constructions and operations in 45 which the speed, skimming force and rate of feed are not maintained in proportionate relation throughout speed changes or in which the load does not vary with the force.

Having described my invention, I claim:

50 1. In a centrifuge machine, a revoluble bowl having an outlet adapted for exhausting it and an inlet through which feeding is effected by the exhausting action, in combination with a guard for said inlet, and 55 means for holding a supply of liquid in communication with said inlet.

2. In a centrifugal machine, a revoluble bowl having an outlet adapted for exhausting it and an inlet through which feeding is 60 effected by the exhausting action, in combination with means for lessening the agitation of liquid in proximity to said inlet and facilitating the suction of said liquid through said inlet.

3. In a centrifugal machine, liquid supply means, in combination with a revoluble bowl having a bottom inlet and higher outlets adapted for sucking liquid from said supply means through said inlet, and means (in addition to said supply means) providing a passageway communicating with said inlet and adapted to be sealed by the liquid supply.

4. In a centrifugal machine, liquid supply means, a revoluble bowl having a bottom inlet and higher outlets adapted for exhausting the revolving bowl and sucking liquid from said supply means through said inlet, in combination with means for both steady- 75 ing the bottom of the bowl and conveying 80 liquid from said means to said inlet.

5. In a centrifugal machine, a suspended revoluble bowl having an axial bottom boss containing an inlet and higher discharge 85 passages adapted for exhausting the revolving bowl, so that liquid adjacent to said inlet will be sucked therethrough, a liquid supply means with which said inlet communicates and from which liquid is sucked into said bowl, and a steadyng device en- 90 gaging said boss and opposing frictional resistance to lateral movement of the revolving bowl.

6. In a centrifugal machine, a suspended 95 revoluble bowl having a bottom boss containing an inlet, a case in which said bowl revolves, a shell seated in the bottom of said case and having an inwardly projecting flange, a ring on said boss in engagement with said flange, a spring for holding said 100 ring in engagement with said flange, means for supporting said spring, liquid supply means, and means whereby liquid is sucked from said supply means through said inlet.

7. In a centrifugal machine, a suspended 105 bowl having a bottom boss containing an inlet and top passages for exhausting said bowl so as to suck liquid through said inlet, a case in which said bowl revolves, a shell seated in the bottom of said case and sur- 110 rounding said boss, said shell having an inwardly projecting flange, a ring on said boss coacting with said flange, a spring acting against said ring, a thimble holding said spring and a vessel from which liquid is 115 drawn through said thimble to said inlet.

8. In the art of centrifugally separating fluids the method which consists in effecting an approximately constant ratio between the square of the revolutions of the 120 revolving separating means and the supply of fluid to be separated throughout speed changes.

9. In a centrifugal machine, a revoluble bowl having a feed inlet, a free untrapped 125 outlet for a lighter constituent to be separated, and a constricted air outlet whereby suction feeding is effected.

10. A centrifugal machine having means for feeding and separating liquid at a rate approximately proportional to the square of the revolutions of the centrifuge, said 5 means comprising a revolute bowl having inlet and outlet passages for material to be separated therein by centrifugal force,

and an outlet for exhausting air from said bowl to effect suction feeding through said inlet, said bowl having means for admitting 10 air to modify the exhausting action.

In testimony whereof I have hereunto set my name this 24th day of April, 1915.

L. P. SHARPLES.
